DESIGN FOR A DISH

James E. Spence, Wheeling, W. Va., assignor to
J. Hungerford Smith Company, Rochester,
N. Y., a corporation of New York

Application April 19, 1937, Serial No. 68,877

Term of patent 7 years

To all whom it may concern:

Be it known that I, James E. Spence, a citizen of the United States, residing at Wheeling, in the county of Ohio and State of West Virginia, have invented a new, original, and ornamental Design for a Dish, of which the following is a specification, reference being had to the accompanying drawing forming part thereof.

I claim:

The ornamental design for a dish as shown.

JAMES E. SPENCE.
